UNITED STATES PATENT OFFICE.

HARRY M. SMITH, OF DALY CITY, CALIFORNIA, ASSIGNOR TO THE COLMAR BURNER COMPANY, OF SAN FRANCISCO, CALIFORNIA, A CORPORATION OF CALIFORNIA.

GAS-GENERATOR.

1,349,923.

Specification of Letters Patent. Patented Aug. 17, 1920.

Application filed May 19, 1919. Serial No. 298,006.

To all whom it may concern:

Be it known that I, HARRY M. SMITH, a citizen of the United States, residing at Daly City, in the county of San Mateo and 5 State of California, have invented new and useful Improvements in Gas-Generators, of which the following is a specification.

My invention relates more specifically to a device adapted to be secured to a hydro- 10 carbon generator for removing the carbon deposits formed therein during the operation.

A main object of my invention is to provide a simple mechanism designed to be secured to the valve rod of a tubular hydro-carbon generator, whereby the interior surface of the tubular member may be effect- 15 ually freed of carbon deposits formed during its operation.

20 A further object of my invention is to provide a carbon removing means for hydro-carbon generators of the tubular type that will permit of a flow of fuel from one end to another during its operation.

25 A further object of my invention is to provide a carbon cleaning or removing device for hydro-carbon generators that will retard the flow of fuel passing through the generator, in order that the liquid fuel may be com- 30 pletely gasified.

35 A still further object of my invention is to provide a resilient cleaning device for hydro-carbon generators, whereby the device will always be forced into contact with the interior surface of the generator tube.

40 Further objects and advantages will appear from the following description, reference being had to the accompanying drawings forming a part thereof in which:

45 Fig. 1 is a longitudinal section through a hydro-carbon generator showing my cleaning device attached thereto.

Fig. 2 is a transverse section through the generator inlet valve taken on the line 2—2 45 of Fig. 1.

50 Fig. 3 is an enlarged fragmental longitudinal section illustrating the method of securing the carbon cleaning means to the generator.

55 Referring more specifically to the drawing, 5 designates the upper portion of a hydro-carbon burner provided with flame slots 6, which are adapted to direct the flames from the burner against the generator dur- 55 ing its operation.

My improved generator preferably consists of a cylindrical tube 7 formed of steel or other suitable material and provided on its outlet end with a plug 8 having a centrally disposed gas outlet orifice 9, the said 60 orifice at its outlet end being enlarged and interiorly threaded for the reception of a detachable burner tip (not shown). The rear end of plug 8 is of reduced diameter and is provided with a centrally disposed threaded bore 10, which bore is engaged by the outer end 11 of the generator valve operating rod 12. The extreme outer end of valve operating rod 12 is provided with a needle valve closure 13, the end being of conical 70 form and seating within the inlet end of the gas outlet orifice 9.

The rear end of valve rod 12 is provided on its periphery with a helical groove 15, semi-circular in cross section, and extending to the rear end of the generator valve rod, as clearly shown in Fig. 1 of the drawing. Valve rod 12 is provided with the usual operating handle 16, the inner end of said rod passing through a packing box construction 17 of usual form formed on the outer end of a fuel inlet fitting 18. Fitting 18 is provided with a fuel inlet bore 19 in which is secured a needle valve construction 20 that controls the flow of fuel to the generator from a source of supply (not shown). 75 80 85

Mounted in the helical groove 15 formed in the generator valve rod, is a coiled spring 21 preferably formed of a resilient wire, the ends 22 of said spring being secured to 90 the valve rod in any suitable manner, such as by passing its ends 22 through transverse bores, as clearly shown in Fig. 3 of the drawings.

The upper edges of the coiled spring 21 95 contact with the interior peripheral surface of the generator tube 7, as clearly shown in Figs. 1 and 3 of the drawings. By means of this construction it will be at once apparent that each individual coil of the spring 21 100 will be forced by its resilient action against the interior surface of the generator tube, and that when the valve rod is rotated back and forth within the tube a scraping action will result. 105

It will be further observed that by the employment of a coiled spring that while the fuel will flow from the inlet end in a substantially direct line to the discharge outlet, the coils of the spring will have a 110

retarding effect on the fuel, and thus permit an almost instantaneous conversion of the fuel into combustible gases.

From the above description it will be seen that by providing the valve rod with a resilient coiled spring mounted in the helical groove, that on a rotation of the same all carbon deposits formed on the interior surface of the generator tube during its operation will be effectually removed therefrom, thus insuring a perfect generation of gases from the fuel, and preventing any clogging action of the generator.

What I claim is:

1. In a hydro-carbon generator construction, a generator casing having a fuel inlet port leading thereto and a vapor outlet port leading therefrom, a valve closure rod mounted in said casing and controlling the vapor outlet port, and means mounted on said rod and contacting with the interior surface of said casing to free the same of foreign matter adhering thereto, said means also permitting the fuel to flow in a substantially direct line from the inlet end of said casing to the vapor outlet port, said means tending to retard the flow of fuel through said casing.

2. In a hydro-carbon generator construction, a generator casing having a fuel inlet port leading thereto and a vapor outlet lead-

ing therefrom, a valve closure rod mounted in said casing and controlling the vapor outlet port, and a spring wound around said rod, the coils of said spring contacting with the interior surface of said generator casing to free the same of foreign matter deposited therein on a rotation of the rod, the coils of said spring having a retarding effect upon the flow of fuel from the inlet port to the vapor discharge outlet, whereby to completely vaporize the fuel into a combustible gas.

3. In a hydro-carbon generator construction, a generator casing having a fuel inlet port leading thereto and a vapor outlet port leading therefrom, a valve closure rod mounted in said casing and controlling said vapor outlet port, said valve rod having a peripheral groove arranged in a helical form, a coiled spring mounted in said groove, the ends of said spring being secured to said rod, the peripheral surface of the coils of said spring contacting with the interior surface of the generator casing, and means to operate said rod, whereby on a rotation thereof the spring coils will free the interior surface of said casing of foreign matter.

In witness that I claim the foregoing I have hereunto subscribed my name this 10th day of May, 1919.

HARRY M. SMITH.
